BOTTLE DISPENSER

Edward A. Terhune, Oak Park, Ill.

Application October 4, 1945, Serial No. 620,325

17 Claims. (Cl. 312—46)

1

This invention relates to improvements in coin controlled dispensing machines particularly adapted for bottles, and similar elongated articles, although not limited to such use.

Among the objects of the invention is to provide an especially compact form of upright multiple magazine, with a novel means for lifting and ejecting the articles automatically from the upper ends thereof and discharging them by gravity to a delivery station.

A further object is to provide novel and efficient means for insuring delivery of the articles in predetermined one-by-one order from the separate compartments comprising the multiple magazine.

A still further object is to provide a novel form of delivery chute including barrier means for protecting the mechanism against tampering from the exterior of the casing.

Another object is to provide a simple and efficient arrangement including a mechanical refrigerator unit for cooling the articles in the magazine, and means for storing and pre-cooling additional articles within the cooling space within the casing.

These and other objects of the invention will appear from time to time as the following description proceeds.

In the drawings:

Figure 1 is a perspective view of a coin-controlled bottle dispensing machine constructed in accordance with the invention.

Figure 2 is an enlarged side view of the bottle magazine and delivery mechanism, with part shown in elevation and part in section, and with an intermediate part of the bottle mechanism broken away.

Figure 3 is an enlarged vertical section of the top end of the bottle magazine, and delivery mechanism showing a bottle in delivered position.

Figure 4 is a fragmentary vertical section taken longitudinally of one of the bottle magazines, to show details of the bottle elevator and ejecting means.

Figure 5 is an enlarged detail view, part in section, of the cable winding mechanism.

Figure 6 is a horizontal detail section of the bottle magazine, taken on line 6—6 of Figure 2.

Figure 7 is a detail section of one of the bottle compartments, with the bottles removed.

Figure 8 is a fragmentary detail section of the bottle magazine, showing means for accommodating bottles of a smaller size therein.

Figure 9 is a fragmentary perspective view

2

showing details of one of the electric control switches.

Figure 10 is a detail front view of the bottle magazine, and showing the means for turning a bottle as it is ejected from the upper end of one of the magazine compartments.

Figure 11 is a detail top view of the bottle magazine, and delivery chute, drawn to a somewhat smaller scale than Figure 10.

10 Figure 12 is a fragmentary front view of the ejection and delivery mechanism at the top of the magazine and showing a bottle as it is passing downwardly over the ejection openings to the delivery chute.

15 Figure 13 is a fragmentary top view showing details of the delivery chute.

Figure 14 is a fragmentary top view similar to Figure 8, to illustrate the means for turning a somewhat smaller bottle as it is ejected from the top of the magazine.

20 Figure 15 is a schematic electric diagram of the electric control system employed with the dispensing mechanism.

Figure 16 is a detail section of the refrigerator 25 unit at the top of the cabinet, taken in a vertical plane at right angles to the front wall of said cabinet.

Figure 17 is a detail section taken on line 17—17 of Figure 16.

30 Referring now to details of the embodiment of the invention shown in the drawings, 10 indicates generally a cabinet or casing containing the bottle dispensing mechanism, and also housing the refrigerating mechanism for cooling the bottles 35 therein. The cabinet has a base 11, side walls 12, 12, and a rear wall 13, and top wall 14. A horizontal partition 15 near the top of the cabinet divides the latter into an upper compartment for housing the refrigerating unit indicated generally at

40 16, and a lower compartment for housing the dispensing mechanism indicated generally at 17. Access to the upper compartment is provided by a pair of hoods 18, 18, hinged along opposite sides of the partition 15, and meeting each other across 45 the top of the casing. Access to the lower compartment is provided by a front door 20, hinged to one of the side walls 12.

The bottle dispensing mechanism 17 is mounted as a unit on a platform 25 which is slidably 50 mounted relative to the base 11 so as to permit the entire dispensing mechanism to be inserted or withdrawn as a unit from the cabinet, for assembly or repair. The platform 25 has a pair of parallel spaced angle bars 26, 26, beneath opposite sides, with a pair of axles 27, 27 having

rollers 28 thereon riding on metal tracks 29, 29 on the base 11. Flanges 30 on the angle bars 26 are guided in laterally opening grooved flanges 31 along the tracks 29, as seen in Figures 4 and 5 to prevent displacement of the dispensing unit in the event that the cabinet is tilted.

A plurality of bottle compartments or magazines, herein four in number, indicated at 33, 34, 35 and 36, are mounted on the platform 25. Said compartments are disposed in upright parallel relation immediately adjacent each other, the front compartment 33 having a front wall 31, the intermediate compartments having common upright parallel partitions 38, 39 and 40 separating them, and the rear compartment 36 having a rear wall 41. The compartments are generally similar in structure, excepting that they are of graduated height from front to rear, to assist in discharging the bottles by gravity therefrom, as will presently appear.

Each magazine compartment has end walls 42, 43 with slots 44, 45 extending from top to bottom thereof, to form guideways for opposite ends of a bottle elevator 46 in each compartment. The upper ends of the compartments have frame members 47, 48 along their sides.

Each of the magazine compartments is preferably provided with a pair of vertically disposed angle bars 102, 102 fixed along its front and rear walls to form a restricted vertical space for receiving the necks of the bottles therebetween, and keeping the bottles in vertically aligned relation with each other.

Each bottle elevator 46 has a widened platform 50 near one end mounted on a transverse shaft 51 which extends through and is suitably guided in the slots 44, 45 at opposite ends of the compartment. In the form shown, the shaft 51 has a guide roller 52 mounted at one end, to limit endwise movement of the shaft and its platform in the compartment. The platform has a relatively short guide lug 53 at one end which projects through the adjacent end slot 44 below the shaft 51, and also has an extended guide lug 54 at the other end, which projects through the opposite end slot 45, as seen in Figure 4. The upper surface of the widened platform 50 is slightly inclined forwardly, to aid in discharging the bottle therefrom, as will presently appear.

Each of the elevators 46 are supported for vertical movement in their respective magazine compartments by a pair of continuous cables 55, 55, one of which is trained alternately in a serpentine path over pulleys 56, 57, 58, 59 and 60, rotatably mounted in spaced relation along the side frame member 47, and pulleys 61 rotatably mounted on an end of each shaft 51 of each of the elevators 46, as is best seen in Figure 2. The other cable 55 is similarly trained over like disposed pulleys on the frame member 48 at the opposite side of the compartments. Both cables are suitably anchored at their rear ends, as by turnbuckles 64 fixed to the end wall to the rear of the rear magazine compartment 36.

The cables 55, 55 are drawn in and paid out at the same speed by a winding device 65, herein consisting of a pair of drums 66, 67 fixed on a common shaft 68 journaled in a pair of bearing fixtures 69, 69 on the platform 25 at the front of the compartments. In the form shown, the drums are enclosed in similar casings 70, 70 suitably fixed to the platform and each having a plurality of rollers 71, 71 arranged thereabout in close proximity to the helically grooved peripheries of said drums, so as to prevent accidental

displacement of the cables 55, from their respective grooves. The cables pass through a transverse opening at the rear of the drum casings 70 and thence upwardly to the first pulleys 56 adjacent the top of the front compartment as seen in Figure 2.

The drum shaft 68 is driven by an electric motor 75, through a suitable speed reduction mechanism in casing 76, and a sprocket and chain drive indicated generally at 77. The gear casing 76 is pivotally mounted at its inner end on a frame 78 supported on the bearing fixtures 69, 69 above the drum casings 70, 70. The outer end of said gear casing is adjustable relative to said frame, as by a threaded member 78a to vary the tension of the chain drive.

Means are provided for reversing the cable drums at will, in the form showed herein, such reversal being accomplished by providing an electric motor of the reversible type, with starting and reverse switching means responsive to various operating control devices, as will presently appear.

It may be explained at this point, that when the magazine compartments are each filled with bottles 80, 80, the elevators 46 are positioned in their lowermost positions, as shown in Figure 4, and that winding of the drums 66 and 67 will tend to cause said elevators to rise in their respective magazine compartments to eject the bottles from the upper ends of said compartments. It will be observed, however, that the several compartments are of increasing height, and correspondingly different bottle capacities, from front to rear. This condition, plus the cumulative friction of each successive pair of pulleys over which the cables 55 are trained, insures an initial discharging movement of the elevator in the front compartment, so that the bottles will first be discharged from the front compartment, and the latter will become fully emptied before the elevator in the second compartment starts to rise. This complete emptying action is repeated for each of the succeeding compartments, until all of the compartments are emptied.

The successive discharge of bottles from the several compartments as just described is in part automatically controlled and directed by a plurality of flaps 83, 84, 85 and 86, having their rear edges hinged, respectively, along the front walls of each compartment at the upper discharge opening thereof. The front edges of each of the flaps 84, 85 and 86 project along the ends of said compartments in which the larger ends of the bottles are disposed, and each of the upper flaps overlap the rear hinged edges of the next lower flap, so that all of said flaps normally close the left ends of the upper discharge openings, in downwardly inclined, cascade relation as seen in Figures 3 and 11.

The hinged flaps 84, 85 and 86 are each provided with substantially upright flanges 84a, 85a, and 86a, respectively, along their outer ends, and with forwardly conveying inclined flanges 84b, 85b, and 86b, respectively, along their opposite inner ends, to assist in directing the bottles from the upper discharge opening at the upper end of the rear compartment and across the lower discharge openings of the other compartments to the delivery chute.

The lowermost flap 83 is somewhat wider than the three upper flaps, and end flanges are unnecessary in this case. Said lower flap forms part of the automatic control mechanism, responsive to the passage of a bottle thereover

for actuating a switch 90 of the electric control system mounted on the outer wall of the discharge chute 106 to cut off current to the motor 75. In the form shown, said lower flap 83 is yieldingly supported by a leaf spring 91 on switch 90 of the well known "microswitch" type, so that said flap normally assumes a slightly elevated position relative to the upper flaps 84, 85 and 86, as shown in Figures 2 and 12. As soon as a bottle is discharged from one of the compartments, it is directed toward the delivery chute, and depresses the lower flap 83 as it passes thereover, to actuate the switch 90.

The upper hinged flaps 84, 85 and 86 may be provided with auxiliary weights 84c, 85c and 86c mounted on the upright end flanges 84b, 85b and 86b, respectively, to assist in holding said flaps by gravity in their fully open position over their respective delivery openings, when loading the compartments.

Means are also provided for controlling the egress of the bottles from the compartment discharge openings, so that they are maintained in proper parallel position during discharge, but will be turned through an angle of 90° immediately after they emerge from their respective compartments so as to pass by gravity with their larger end directed toward the delivery chute.

It will be understood that all of the bottles 80 are initially loaded in the compartments with their larger bottom ends toward the left, and their tops toward the right as seen in Figure 4. Commercial bottles are commonly made with their bodies tapered upwardly slightly from their base. Hence, the bottles at the top of a compartment normally tend to tilt cap downwardly in the compartment, so as to be discharged from their compartment in a slightly tilted position.

To correct this tendency, I provide each compartment, near its upper end, with a generally upright leaf spring 95, preferably fixed to the rear wall near the left end of the compartment, bowed outwardly closely adjacent the discharge opening, as seen in Figure 3. Similar springs 95b may also be mounted at one or more points between the top and bottom of the compartment, as seen in Figure 4. These springs serve to retard the upward passage of the bottles at their bottom ends, thus tending to straighten them into a substantially horizontal position as they are ejected from their respective compartment openings.

Each of the hinged flaps 84, 85 and 86 have bowed strips 94 mounted transversely of their lower faces, forming abutment means to be engaged by the lower ends of the bottles and direct the bottle forwardly as they are ejected from their compartments. Each of the platforms 46 has a recess 95a formed transversely of its upper surface to accommodate the bowed strip 94 on its respective flap, when the platform is in its uppermost position, and its compartment is empty.

The uppermost back compartment requires no hinged flap, but may be provided with an extended, forwardly inclined plate 99 along its rear edge, to urge the larger ends of the bottles forwardly as they are ejected from the rear compartment.

The means for turning the larger ends of the bottles downwardly as they emerge from their respective compartment openings is illustrated in detail in Figures 10, 11 and 12. Each compartment has an upright stop rod 100 fixed, as by bolting to its front partition adjacent the

right end of the compartment, and extending a substantial distance above its respective partition, in position to be engaged by the neck of each bottle as the latter is ejected from its compartment. Thus, assuming that a bottle is being ejected from the top of the rear compartment, as seen in Figures 10 and 11, the larger, bottom end engages the inclined plate 99, and is urged forwardly onto the inclined hinged flap 86, over the next compartment, while the upper end of the bottle is retarded by the stop rod 100. This causes the bottle to be twisted or turned endwise at the same time that it is directed into the inclined chute formed between the end flanges of the flaps 86, 85 and 84, with the result that the bottle will move by gravity over the lower discharge openings and toward the delivery chute, with its larger and heavier end directed toward the latter.

The delivery chute is indicated generally at 105, and includes means for protecting the apparatus from tampering, and preventing the unauthorized delivery of bottles from the machine. In the form shown herein, said chute leads into a housing 106 suitably mounted on the front of the magazine compartments and arranged to project forwardly into proximity to the hinged front door 20, with the delivery opening 107 registering with a framed opening 108 in said door. The delivery chute includes a platform 109, hinged by pin 111 intermediate its ends on a support 112 and normally disposed at an inclined angle substantially in alignment with the flaps 84, 85 and 86 of the magazine compartments, and has its rear end extending beneath the lower flap 83, which is hinged to the front edge of the front compartment as previously described.

The front end of the tilting platform 109 has a depending member fixed thereon, including an arcuate front surface 113 arranged to swing in close proximity to an upright cross member 114 fixed to the bottom of the housing 106 to normally partially close the delivery opening 107. The arrangement is such, that when a bottle is discharged and slides downwardly from one of the magazine delivery openings, it passes bottom forward along the tilting platform 109 and beyond the hinge pin 111 until the weight of the bottle serves to tilt the platform downwardly into the position shown in Figure 3. In this latter position, the lower end of the tilting platform 109 is brought into alignment with the inclined front face 115 of the upright cross member 114 at the bottom of the casing. The bottle finally comes to rest with its bottom end against a cushion 116, which is fixed at an inclined angle in the bottom sill 118 of the framed opening 108 at the front door 20.

In this position the sides of the bottle rest partially against the inclined surface 115 of the cross member 114, but it also engages the front edge of the tilting platform at its upper end, so as to prevent the return of said platform to its normal raised position until the bottle is removed from the delivery opening 107 by hand.

Means are also provided for temporarily retarding the movement of the bottle through the delivery chute just described, consisting of a buffer plate 119, hinged at its upper end in the housing 106 and depending into the path of the bottle just above the lower end of tilting platform 109, when the latter is in its normal raised position. The end of the bottle strikes this buffer plate as it slides along the platform.

Means are also provided for adjusting the effec-

tive weighting of the buffer plate 119, by a container 120 fixed on the rear of said plate and open at its top, for reception of one or more weights 121, as required for bottles of different weights. The lower end of the hinged buffer plate 119 may also be provided with a cushion 122 to absorb excessive shocks when said plate swings into contact with the adjacent front wall of the housing 106.

The rear, shorter end of the tilting platform 109 may be provided with a hinged auxiliary weight 123, if necessary, to counterbalance the longer front end of said platform.

Further means are provided to prevent access to the apparatus through the delivery chute, herein consisting of an arcuately shaped metal hood 125, fixed to the upper surface of the tilting platform 109 just in front of its pivotal axis, to form an elongated restricted opening along said platform only of sufficient diameter to permit the bottle to pass therethrough. In addition, another hood 126 is fixed on the housing 106, with its front opening substantially in registry with the rear edge of the movable hood 125 on the tilting platform, when the latter is swung upwardly in normal position. The rear portion of the fixed hood 126 is slightly flared outwardly, to assist in guiding the bottom of each bottle into proper endwise alignment as it enters the movable hood 125 on the tilting platform.

A baffle plate 127 is also hinged near the top of the fixed hood 126, and arranged so that it substantially closes the latter. Said baffle plate is provided with projecting stop means 128 so that said baffle plate can only be opened by swinging in a forward direction.

The movable hood 125 forms in effect, a restricted cuff, to limit the insertion of a hand or fingers through the delivery opening, and the hinged baffle plate or gate 127 in the fixed hood 126 further protects the apparatus from the insertion of picks or like tools which may be projected through the delivery opening in an effort to tamper with the operating mechanism.

As a still further protection against tampering, it will be observed that when the platform 109 is tilted upwardly, it also tilts the flap 83 upwardly, as shown in Figure 3, so as to provide an additional positive barrier to the interior of the mechanism, especially when the front end of the tilting platform 109 is in its relatively opened position.

The apparatus is also provided with means for accommodating the magazine compartments to bottles of different commercial sizes. As shown in Figures 10, 11 and 12, the stop pins 100 and angle bars 102, 102 in each of the compartments are arranged to receive bottles of a large commercial size, such as a 12 oz. bottle.

Figures 8 and 14 show how the compartments can be readily adjusted to handle smaller bottles, such as a six oz. size, by adjusting the position of the stop pins 100 inwardly to a position within the angle bars 102, 102, and affixing a second, slightly deeper row of angle bars 103, 103 along front and rear walls of each compartment, to provide end abutments for the caps of the shorter bottles. In case the bodies of the bottles are of smaller diameter, a plurality of pairs of auxiliary spacer rods 104 and 105 can also be fixed along the front and rear walls opposite the wider ends of the bottles. Thus, the same machine can be quickly changed to accommodate various commercial sizes of bottle.

The operation of the electric motor 75 for caus-

ing successive ejection of the bottles from the magazine compartments is controlled primarily by a coin-operated mechanism 215, which may be of a conventional form, mounted on the front door 20, and arranged as usual to close a switch 216 when a coin is inserted in a slot 217 in the front of the casing. The coin-operated mechanism is of the kind well known in the art, and details thereof need not be described or shown herein, as it forms no essential part of the present invention.

The electric circuit for operating the motor, together with the several control devices associated therewith, will now be described, in connection with the schematic electric diagram, Figure 15.

Current is supplied from main line conductors 220 and 221, which may, for instance, consist of the usual commercial alternating current lighting circuit.

The coin controlled switch 216 is connected in line 222 in series with a relay 223 and the microswitch 98, which is normally closed, but is opened when a bottle, discharged from one of the compartments, passes over and depresses the lower flap 83, as previously described. The relay 223 operates to close switch 223a in line 225 connected to line 226 having relay 227 and microswitch 228 therein.

30 The microswitch 228 is a forward limit switch, located at the upper end of the rear compartment, and arranged to be opened by engagement by the elevator 46 therein after the last bottle has been discharged from the machine, thus protecting the mechanism from breakage.

Relay 223 also closes switch 223a in parallel with the coin-controlled switch 216 to maintain current through line 222 after switch 216 has been initially closed by passage of a coin through the coin operating mechanism.

The relay 227 operates to close switches 227a and 227b in the motor leads 228 and 229, respectively, and also the switch 227c in the motor lead 230. When the relay 227 is energized, the motor will operate in its forward direction, to wind in the cable drums.

A branch line 231 from line 225 leads to a double pole, manually operated reversing switch 232, which is manipulated by a toggle switch lever 233 preferably mounted at a suitable point within the cabinet. The switch lever 233 is connected to a line 234, which is connected to the main line 220 through microswitch 235 and to the main line 221 through a flood light 236.

55 The microswitch 235 is arranged to be automatically closed when the front door 20 is opened, to light the flood light 236 within the magazine compartment. It also disconnects the reversing switch lever 232 when the door is closed, so the latter switch is only operable for reversing the motor when the door is open.

The toggle switch lever 232 can be selectively connected to the line 231 for operating the motor in the forward direction, or to the line 237, leading through relay 238 and microswitch 239 to the main line 221.

The motor reversing circuit through lines 229 and 230 with relays 227a, 227b, 238b and 238c constitutes a conventional reversing circuit, which need not be further described herein.

The microswitch 239 is a reverse limit switch, located at the bottom of the first compartment, and is automatically opened by engagement by the elevator 46 in said compartment after said elevator has reached the bottom of said compart-

ment, and the magazines are fully loaded, so as to prevent overrunning of the cables on the cable drums.

The control mechanism also includes a coin acceptance magnet 240 in line 241, connected by a double throw microswitch 242 to main line 220, and leading through a normally closed switch 223b, and thence through a microswitch 243 in the motor lead 244 to the main line 221.

The coin acceptance magnet forms a usual part of the commercial coin mechanisms. As used herein, it serves its usual function of rejecting and returning a bad coin, by causing a coin to by-pass coin switch 216 and returning said coin to the customer. The microswitch 242 is located near the upper end of the rear compartment, in position to be actuated by the elevator 46 therein when the last bottle is being ejected therefrom, to cause any coins inserted in the machine to be returned, and also to connect the current to a signal light 245, suitably mounted on the front door of the casing, to show that the machine is empty.

Microswitch 243 is located in the delivery housing 106 in position to be opened by the delivery platform 109 when it is tilted downwardly into final delivery position. Said switch is held in open position, to render the motor inoperable, until the bottle in the delivery opening is removed and the tilting platform restored to its raised position.

Moreover, microswitch 243 is located relative to the tilting platform 109 so that switch 243 will be opened before said platform engages and raises the flap 83 thus causing the latter flap to open switch 90, when one bottle passes thereover, and preventing delivery of two bottles at one time, by manipulating the tilting platform through the delivery opening.

The principal features of operation of the electric control mechanism just described may now be briefly reviewed. The discharge of the bottles in successive order from the magazine compartments is normally effected solely by operation of the motor 75 in its forward position, in response to insertion of a coin in the coin operating mechanism. The coin acceptance magnet 240 prevents the motor starting circuit from closing, however, whenever an improper coin is inserted.

When the last compartment is emptied, the microswitch 242 energizes the "empty" signal light 245. The forward limit switch 228 also cuts off any further operation of the motor, until the supply of bottles has been replenished.

The opening of the door to the interior of the casing automatically cuts in a selectively operable, reversible motor circuit, capable of manual control through the toggle switch 232, located within the casing. The motor reversing circuit is designed to permit the loading of the magazine compartments.

Referring now to details of the refrigerating unit 16 for the cabinet, which is housed in the upper compartment and enclosed by the hinged hoods 18, 18 as previously mentioned, said unit may consist of any well-known refrigerating mechanism, including a compressor 150, a condenser 151, and the usual associated parts, all mounted on a platform 152. Said platform includes a pair of spaced side frame members 153, 153 slidably mounted on tracks 154, 154 along opposite sides of the horizontal partition 15, so that the entire refrigerating mechanism can be assembled or removed from the cabinet

as a unit, for replacement by another unit when repairs are necessary.

The refrigerator unit is held against accidental displacement by a pair of arcuate bosses 161, 161 depending from each of the side frames 153 of the platform 152, which bosses set into depressions 162, 162 in the tracks 154, 154, when the unit is in proper registering position relative to the cooling aperture 158.

10 In the arrangement shown herein, the refrigerating unit includes a cooling coil 155, mounted in an insulated casing 156, adjacent the rear end of the cabinet. The casing 156 has a relatively large opening 158 at its bottom, registering with a cooling aperture 157 formed in the top partition 15 of the dispensing magazine compartment, when the refrigerating unit is in normal assembled position in its upper compartment.

The juncture between the openings 157 and 158 is normally sealed by a flexible gasket 159, surrounding the bottom margin of the casing 156.

20 The cooling coils have a fan 159 arranged in the casing 156, with a baffle plate 160 arranged for producing circulation of cooled air downwardly along one side of said casing, and a return current upwardly along the other side thereof, said circulating air current being continued through the cooling aperture 158 into communication with the lower compartment, so as to cool the latter, as indicated in Figure 17. Thus the entire refrigerating unit can be removed from or replaced on the partition 15 without disconnecting the cooling coils from the condenser and its associated parts.

25 The condenser 151 of the refrigerating unit is cooled as usual by fan circulated air, passing through louvers 164 formed in the sides of the hoods 18, 18.

30 It will now be understood from the above description that the general arrangement of the upright magazine compartments, with ejection openings at the top thereof, together with the refrigerator unit mounted above the delivery mechanism compartment, affords several distinct advantages in a bottle dispensing machine. For instance, the magazines and the delivery mechanism are especially compact in construction, permitting storage of a maximum number

35 of bottles in a given space. The top ejection of the bottles permits the delivery chute to be disposed most conveniently at a relatively high level on the front of the cabinet, and still permits the refrigerator unit to be mounted above the delivery mechanism, in the most efficient position for cooling the contents of the cabinet and servicing the unit, without encroaching upon or interfering with the operation of the delivery mechanism. The refrigerating unit is well above the floor, to avoid dust and dirt, which tends to clog the condenser and reduce the efficiency of the unit.

40 Although I have shown and described certain embodiments of my invention, it will be understood that I do not wish to be limited to the exact construction shown and described, but that various changes and modifications may be made without departing from the spirit and scope of the invention as defined in the appended claims.

45 70 I claim:

50 1. In a dispensing machine, a plurality of parallel upright magazine compartments, each having an elevator for supporting articles to be dispensed therefrom, means for actuating said elevators in consecutive order by step-by-step

movement to eject the articles one by one from openings at the tops of said compartments, the ejection openings of said compartments being disposed in cascade relation to each other, and means for bridging each of the lower ejection openings to form a continuous chute for guiding an article by gravity from a higher opening across each lower opening to a discharge station.

2. In a dispensing machine, a plurality of parallel upright magazine compartments, each having an elevator for supporting articles to be dispensed therefrom, means for actuating said elevators in consecutive order by step-by-step movement to eject the articles one by one from openings at the tops of said compartments, including continuous flexible cable means operatively engaged with said elevators in the aforesaid consecutive order and a winding device for said cable means.

3. In a dispensing machine, a plurality of parallel upright magazine compartments, each having an elevator for supporting articles to be dispensed therefrom, means for actuating said elevators in consecutive order by step-by-step movement to eject the articles one by one from openings at the tops of said compartments, including continuous flexible cable means operatively engaged with said elevators in the aforesaid consecutive order and a winding device for said cable means, the ejection openings of said compartments being disposed in cascade relation to each other, and means for bridging each of the lower ejection openings to form a continuous chute for guiding an article by gravity from a higher opening across each lower opening to a discharge station.

4. In a dispensing machine, a plurality of parallel upright magazine compartments, each having an elevator for supporting articles to be dispensed therefrom, means for actuating said elevators in consecutive order by step-by-step movement to eject the articles one by one from openings at the tops of said compartments, including a pair of continuous flexible cables, pulleys on the opposite ends of all of said elevators operatively engaged by said cables respectively in the aforesaid consecutive order, and a single winding device for said cables.

5. In a dispensing machine, a plurality of parallel upright magazine compartments, each having an elevator for supporting articles to be dispensed therefrom, means for actuating said elevators in consecutive order by step-by-step movement to eject the articles one by one from openings at the tops of said compartments, including a pair of continuous flexible cables, pulleys on the opposite ends of all of said elevators operatively engaged by said cables respectively in the aforesaid consecutive order, and a single winding device for said cables, the ejection openings of said compartments being disposed in cascade relation to each other, and means for bridging each of the lower ejection openings to form a continuous chute for guiding an article by gravity from a higher opening across each lower opening to a discharge station.

6. In a dispensing machine, a plurality of parallel upright magazine compartments, each having an elevator for supporting articles to be dispensed therefrom, means for actuating said elevators in consecutive order by step-by-step movement to eject the articles one by one from openings at the tops of said compartments, the ejection openings of said compartments being disposed in cascade relation to each other, and

flaps movably mounted over and bridging each of the lower ejection openings to form a continuous chute for guiding an article by gravity from a higher opening across each lower opening to a discharge station.

5. In a dispensing machine, a plurality of parallel upright magazine compartments, each having an elevator for supporting articles to be dispensed therefrom, means for actuating said elevators in consecutive order by step-by-step movement to eject the articles one by one from openings at the tops of said compartments, the ejection openings of said compartments being disposed in cascade relation to each other, and flaps movably mounted over and normally closing the lower ejection openings to form continuous chute sections for discharging the articles by gravity across each lower opening from any higher ejection opening.

10. In a dispensing machine, a plurality of parallel upright magazine compartments, each having an elevator for supporting elongated articles to be dispensed therefrom, means for actuating said elevators in consecutive order by step-by-step movement to eject the articles one by one from openings at the tops of said compartments, the ejection openings of said compartments being disposed in cascade relation to each other, means for guiding an article by gravity from a higher opening across each lower opening to a discharge station, and means at each ejection opening for turning each article and directing it endwise as it leaves its respective opening and moves by gravity toward said discharge station.

20. In a dispensing machine, a plurality of parallel upright magazine compartments, each having an elevator for supporting elongated articles to be dispensed therefrom, means for actuating said elevators in consecutive order by step-by-step movement to eject the articles one by one from openings at the tops of said compartments, the ejection openings of said compartments being disposed in cascade relation to each other, flaps movably mounted over and bridging each of the lower ejection openings to form a continuous chute for guiding an article by gravity from a higher opening across each lower opening to a discharge station, and abutment means at one end of said ejection opening for initially directing one end of a bottle toward said chute as it emerges from its ejection opening, and a fixed abutment adjacent the other end of said ejection opening, for turning each article and directing it endwise as it leaves said opening and moves by gravity toward said discharge station.

25. In a dispensing machine, a plurality of parallel upright magazine compartments, each having an elevator for supporting elongated articles to be dispensed therefrom, means for actuating said elevators in consecutive order by step-by-step movement to eject the articles one by one from openings at the tops of said compartments, the ejection openings of said compartments being disposed in cascade relation to each other, flaps movably mounted over and bridging each of the lower ejection openings to form a continuous chute for guiding an article by gravity from a higher opening across each lower opening to a discharge station, and abutment means at each ejection opening for initially directing one end of a bottle toward said chute as it emerges from its ejection opening, including an abutment on the bottom of each of said flaps adjacent one end thereof, and a fixed abutment adjacent the other end of said ejection open-

ing, for turning each article and directing it endwise as it leaves said opening and moves by gravity toward said discharge station.

11. In a dispensing machine, a plurality of parallel upright magazine compartments, each having an elevator for supporting articles to be dispensed therefrom, means for actuating said elevators in consecutive order by step-by-step movement to eject the articles one by one from openings at the tops of said compartments, the ejection openings of said compartments being disposed in cascade relation to each other, flaps movably mounted over and bridging each of the lower ejection openings to form a continuous chute for guiding an article by gravity from a higher opening across each lower opening to a discharge station, and means responsive to the passage of an article along said chute for rendering said elevator actuating means temporarily inoperative.

12. In a dispensing machine, a plurality of parallel upright magazine compartments, each having an elevator for supporting articles to be dispensed therefrom, means for actuating said elevators in consecutive order by step-by-step movement to eject the articles one by one from openings at the tops of said compartments, the ejection openings of said compartments being disposed in cascade relation to each other, and flaps movably mounted over and bridging each of the lower ejection openings to form a continuous chute for guiding an article by gravity from a higher opening across each lower opening to a discharge station, and a hinged control flap below and in series with said first-named flaps engaging control means for rendering said elevator actuating means temporarily inoperative when said control flap is depressed by the weight of an article passing thereover.

13. In a dispensing machine, a plurality of parallel upright magazine compartments, each having an elevator for supporting articles to be dispensed therefrom, means for actuating said elevators in consecutive order by step-by-step movement to eject the articles one by one from the upper ends of said compartments, the upper ejection openings of said compartments being disposed in cascade relation to each other, and movable flaps hinged adjacent the rear edges of said ejection openings for bridging each of the lower ejection openings to form a continuous chute for guiding an article by gravity from a higher opening across each lower opening to a discharge station.

14. In a dispensing machine, a plurality of parallel upright magazine compartments open at the upper end, each having an elevator for supporting articles to be dispensed therefrom, means for actuating said elevators consecutively to eject the articles one by one in predetermined order from the upper ends of said compartments, including pulleys on said elevators, other pulleys fixed on the upper ends of said compartments intermediate adjacent compartments, flexible

cable means trained alternatively over said elevator pulleys and said fixed pulleys, and power winding means for said cable means.

15. In a dispensing machine, a plurality of parallel upright magazine compartments open at the upper end, each having an elevator for supporting articles to be dispensed therefrom, means for actuating said elevators consecutively to eject the articles one by one in predetermined order from the upper ends of said compartments, including pulleys on said elevators, other pulleys fixed on the upper ends of said compartments intermediate adjacent compartments, flexible cable means trained alternately over said elevator pulleys and said fixed pulleys, power winding means for said cable means, coin operated control means for starting said power winding means, and other control means responsive to the ejection of an article from any one of said compartments for rendering said power winding means inoperative.

16. In a dispensing machine, a casing having a delivery opening, an article magazine in said casing, means for ejecting articles from said magazine and discharging them by gravity toward said delivery opening including a movable chute portion, a rockable delivery platform at said delivery opening beyond said chute normally inaccessible from the exterior of said casing, but tiltable by the weight of an article thereon to move the latter into accessible position in said delivery opening, said platform being connected with said chute portion for moving the latter into non-delivering position when said platform is tilted into delivery position.

17. In a dispensing machine, a casing having a delivery opening, an article magazine in said casing, means for ejecting articles from said magazine and discharging them by gravity toward said delivery opening including a movable chute portion, a rockable delivery platform at said delivery opening beyond said chute normally inaccessible from the exterior of said casing, but tiltable by the weight of an article thereon to move the latter into accessible position in said delivery opening, said platform being connected with said chute portion for rocking said chute portion upwardly to prevent access to said article magazine from the exterior of the casing when said platform is tilted into delivery position.

EDWARD A. TERHUNE.
